DEVICE FOR SORTING AND ORIENTING
BLANKS HAVING PORTIONS OF DIFFER-
ENT TRANSVERSE DIMENSIONSFrank B. Davis, Lakewood, Ohio, assignor to The
Lamson & Sessions Company, Cleveland, Ohio,
a corporation of Ohio

Application February 23, 1945, Serial No. 579,439

3 Claims. (Cl. 209—72)

1

This invention relates to a sorting device adapted to feed shouldered studs, shouldered blanks and the like into a tube or chute so that they will emerge from the tube in a definite position as regards the large end and the small end.

I have designed this sorting device for use with roll thread dies but it may have use in connection with other type of machines, this device operating in a manner such that the blanks will be presented always in the desired position to the roll thread dies or other equipment.

One of the objects of the invention is to have the blanks feed automatically in proper position with the large end down, in which case the large end of the blank will be automatically presented to the roll thread dies so as to have the thread rolled on the larger diameter.

Another object of the invention is to have the blanks fed automatically in proper position with the small end down, when it is desired that the blanks be presented to the roll thread dies so as to thread the smaller ends of the blanks.

The invention may be further briefly summarized as consisting in certain novel details of construction and combinations and arrangements of parts which will be described in the specification and set forth in the appended claims.

In the accompanying sheets of drawings illustrating my invention,

Fig. 1 is a front view of my improved sorting device, a portion only of the machine which operates on the blanks being shown, this view showing the spring strips arranged for feeding the blanks with the large end down;

Fig. 2 is a side view of the same;

Fig. 3 is a fragmentary sectional view on an enlarged scale as viewed in Fig. 1 showing the device adjusted for the purpose of feeding the blanks from the revolving ring in the hopper with the large end down;

Fig. 4 is a fragmentary sectional view on an enlarged scale of the construction shown in Fig. 3, i. e., the arrangement wherein the blanks are fed with the large end down, this section being taken substantially along the line 4—4 of Fig. 3;

Fig. 5 is a view similar to Fig. 3 but showing an arrangement wherein the blanks are fed to the tube or chute with the small end down; and

Fig. 6 is a view similar to Fig. 4 of the arrangement shown in Fig. 5.

As will be seen by reference particularly to Figs. 1 and 2, the sorting device is secured to a bracket 10 which, in turn, is secured to the upper part of the thread rolling machine or other equipment to which the sorting device is applied. The

2

sorting device includes a stationary hopper 11 which is mounted in an inclined position as shown. At the center of the hopper 11 is a stationary portion 12 from which extends a projection 13 to be referred to presently. Mounted for rotation between the periphery of the hopper and the stationary central portion 12 is a rotary ring 14 which is driven at the desired speed by an electric motor 15 with suitable reduction gearing and the casing therefor indicated as a whole by the reference character 16, the part 16 including not only reduction gearing but the rotation transmitting shafts. In Figs. 4 and 6 I have shown at 14a, near the inner periphery of the ring 14, the gear which is engaged by the driving pinion, not shown. The rotary ring 14 has a series of radially disposed grooves 17 of a depth slightly less than the maximum diameter of the blanks to be handled in the device. A quantity of the blanks are dumped into the hopper and, to insure their deposit in the grooves 17, I provide on the upper face of the rotary ring 14, near its outer periphery, a suitable number of angles 18 with up-standing flanges. These angles are in this instance arranged adjacent each alternate groove 17, so as to agitate the blanks which lie in the lower part of the hopper and cause them to enter the grooves 17.

There is secured to the stationary projection 13 a tube or chute, which in Figs. 2 and 4 is designated 19. It will be noted, particularly by reference to Figs. 2 and 4, that the tube 19 is of somewhat less inclination than the hopper. This tube 19 is of a diameter such that the blanks may pass through the same. The upper end of the tube 19 terminates slightly inwardly of the inner periphery of the rotary ring 14 and the upper end of the tube has its upper portion cut away at 20 and is somewhat flattened, as shown at 21 by the dotted lines of Fig. 3. The lower end of the tube 19 has secured to it a continuation in the form of a spring coil 22 which extends downwardly to the point where the blanks are to be delivered one at a time to the machine with which this sorting device is used, such as the thread rolling machine.

Coming now to the parts involving my invention, it will be seen that I secure to the stationary projection 13 either a single spring plate or preferably two spring plates 23 and 23a which extend from the projection 13 upwardly and overlap slightly the rotary ring 14. The two spring plates are preferred because they provide greater flexibility than a single plate. The upper ends 25 of these spring plates are slightly curved up-

wardly, as shown at 24, in Fig. 4, and the upper corner of the spring 23, which the blanks first engage, is slightly bent upwardly, as shown at 25. The upper edges of the plates 23 and 23a are in substantial horizontal alignment, as best shown in Fig. 3.

The blanks on which the threads are to be rolled are designated 26. These blanks each have at one end a portion 26a of enlarged diameter and, at the opposite end, a portion 26b of relatively smaller diameter. Both ends of the blanks are preferably tapered. The shape of the blank is clearly shown in Figs. 3 and 4.

The blanks in the grooves 17 of the rotating ring 14 may obviously have their large ends 26a up or down. In the construction shown in Figs. 1 and 4, the blanks having their large ends down pass through the tube 19, and those having their large ends up are rejected and again fall back into the hopper. A ledge 27 is provided on the annular stationary part 12 of the hopper adjacent the inner periphery of the rotating ring 14 and as the blanks approach the spring plates 23 and 23a they drop down so that their inner ends ride along the upper edge of the ledge 27. The blanks having their large ends down ride under the spring 23 until they reach the upper end of the tube and they fall into the tube and pass down the same and through the coil 22, but the blanks having their large ends up cannot pass down the tube 19 because the shoulder formed at the inner end of the enlarged portion 26a rides along the upper edges of the plates 23 and 23a and after passing the plate 23a they drop back into the hopper. This is illustrated at 26c in Fig. 3. In this manner only the blanks having their large ends down pass into the tube 19, and all of the blanks having their large ends up are rejected and fall back into the hopper.

In Figs. 5 and 6 I have shown an arrangement wherein the blanks pass into the tube with their small ends down, and the blanks having their large ends down are rejected and drop back into the hopper before they reach the end of the tube, which is here designated 28. This tube 28 is quite similar to the tube shown in Figs. 1 to 4 except that the upper end of the tube is somewhat curved just beneath the inner periphery of the rotating ring 14, as shown at 29. In this instance there is secured to the top of the stationary projection 13 a single spring plate 30 which extends upwardly beyond the inner periphery of the rotary ring 14, but two plates may be employed if desired. This plate 30 is split for a distance from its outer end as shown at 31 in Fig. 5, forming at its outer end two sections 30a and 30b. The portion 30b extends upwardly beyond the section 30a and at its upper end is curved downwardly to or substantially to the rotary ring 14. The upper end of the section 30a is bent inwardly and lies on a lower plane than the body portion of the section 30b.

It was above stated in connection with the form of the invention first described that the blanks pass downwardly and ride along a ledge 27 secured to the stationary part 12 of the hopper adjacent the inner periphery of the rotary ring 14. With the construction now being described a portion of the ledge is cut away, as shown at 27a in Fig. 5, the cut-away portion being at the left-hand side of the curved and partly flattened portion 29 of the tube 28. As the blanks pass over the spring sections 30a and 30b, if the blanks have their large ends up they will be held in the grooves by the depressed portion of the spring

section 30a and will be carried over the cut-away portion 27a of the ledge 27, since the depressed part of the spring section 30a engages the larger end 26a of the blank 26 until it passes beyond the division between the sections 30a and 30b of the spring 30, but when the large end of the blank leaves the spring section 30a the blank is released and passes from the groove and drops into the tube 28. It will be noted at this point that the split between the sections 30a and 30b is inclined so that the section 30b extends over the slot when in alignment with the tube and, accordingly, when the blank reaches the section 30b it is no longer held in the groove but may pass from the groove into the tube. If, however, the blank in the slot, as it approaches the section 30a of the spring 30, has its small end up and its large end down the smaller end will not be engaged by the depressed portion of the section 30a of the spring and accordingly when the blank reaches the cut-away portion 27a of the ledge 27 and before it is in alignment with the end of the tube, it will pass through this cut-away portion and will drop back into the hopper.

Thus it will be seen that if the blanks in the grooves 17 of the construction illustrated in Figs. 5 and 6 have the desired smaller diameter ends pointed downward they will be held by the section 30a of the spring plate until they reach the tube 28 and will then drop into the tube, but if they have their large ends down they will not be held by the depressed portion of the spring 30a but will drop back into the hopper before reaching the tube. It will be noted that the split between the sections 30a and 30b of the spring plate 30 is cut on a diagonal line which overlaps the groove 17 of the rotary ring 14 when it is in alignment with the tube 28, so that the blanks having the large ends up are no longer held in the groove by the depressed portion of the section 30a of the spring plate 30 when they pass from beneath the section 30a to the section 30b but are then free to drop down into the tube 28.

It will be noted that in the construction shown in Fig. 3, as well as the construction shown in Fig. 5, the upper portion of the spring plate 23a of Fig. 3 and the upper portion of the spring section 30b of the spring plate 30 shown in Fig. 5, is extended laterally a distance beyond the groove 17 of the rotary ring 14 when the groove is in alignment with the tube 19 of Fig. 3 or the tube 28 of Fig. 5. This extension is provided so that, in case there are two of the blanks 26 in a groove, one above the other, the extension will insure the upper blank being carried far enough so that it will pass well beyond the tube 19 or the tube 28 and will be returned to the hopper without interfering with the lower blank passing into the tube.

Thus it will be seen that I have provided a sorting device wherein the spring plate or plates keep the improperly positioned blank from passing down the chute and prevents the feeding of more than one blank into the chute from any one of the feed grooves. In the first instance the spring plates allow only the blanks with the large end down to pass into the tube and, in the second instance, they allow only the blanks with the small end down to pass into the tube so that, in each instance, only the blanks in the desired position pass to the thread rolling dies or other machine to which the sorting device is applied.

While my improved sorting device has been illustrated and described herein in considerable detail, I do not desire to be confined to the precise details shown but aim in my claims to cover

all modifications which do not involve a departure from the spirit and scope of the invention.

Having thus described my invention, I claim:

1. In a sorting device, a stationary hopper into which shouldered blanks each having a large end and a small end are adapted to be dumped, a rotary ring mounted in the hopper and provided with substantially radial grooves adapted to pick up the blanks and to convey them to the sorting point, a tube having its upper end adjacent the inner periphery of the rotary ring, and a substantially flat spring plate extending upwardly a predetermined distance beyond the tube and into overlying face-to-face relation to said ring, said plate allowing the blanks with the large end down to enter the tube and having an upper edge disposed relative to said ring so as to engage under the shoulder formed by the larger end when the large end is up so that the rotary ring will carry the last mentioned blanks past the tube and permit them to fall back into the hopper.

2. In a sorting device, a stationary hopper into which shouldered blanks each having a large end and a small end are adapted to be dumped, a rotary ring mounted in the hopper and provided with substantially radial grooves adapted to pick up the blanks and to convey them to the sorting point, a tube having its upper end adjacent the inner periphery of the rotary ring, and a substantially flat spring plate extending upwardly a predetermined distance beyond the tube and into overlying face-to-face relation to said ring, said plate having means disposed relative to said ring such that the blanks in the grooves having their large ends up will be pressed by the plate against the rotary ring and carried to the tube so as to drop therein, and so that the blanks having their large ends down and their smaller ends up will be released by the plate and will drop back into the hopper in advance of the tube.

3. In a sorting device, a stationary hopper adapted to contain a quantity of elongated blanks having shouldered portions of relatively large and relatively small transverse dimensions, a ring mounted for rotation in said hopper in a plane which is inclined to the horizontal and having substantially radially extending grooves therein adapted to pick up blanks and convey them to a sorting point, said grooves having a depth which is somewhat less than the relatively large transverse dimension of said blanks, a delivery tube extending downwardly from said hopper and having its upper end at said sorting point and disposed adjacent the inner periphery of said ring for register with said grooves in succession as they traverse said sorting point, and a substantially flat spring plate mounted in said hopper over said tube and having a control portion extending beyond said upper end of the tube and into overlying relation to said ring, said control portion being disposed in face-to-face relation to and closely adjacent to the surface of said ring so as to engage the relatively large portions only of the blanks for preventing the movement into said tube of those blanks which do not occupy a desired position in the grooves.

FRANK B. DAVIS.
